UNITED STATES PATENT OFFICE.

GEORGE R. JARMAN, OF BALTIMORE, MARYLAND.

DESIGN FOR A REFRIGERATING MACHINE CASING OR FRAME.

61,094.

Specification for Design. Patented June 20, 1922.

Application filed June 29, 1918. Serial No. 242,685. Term of patent 3½ years.

To all whom it may concern:

Be it known that I, GEORGE R. JARMAN, a citizen of the United States of America, and resident of Baltimore, in the State of Maryland, have invented a new, original, and ornamental Design for a Refrigerating Machine Casing or Frame, of which the following is a specification, reference being had to the accompanying drawing, forming part thereof.

The figure is an elevational view of the casings and frames of a refrigerating machine, showing my new design.

I claim:

The ornamental design for a refrigerating machine casing or frame, as shown.

GEORGE R. JARMAN.
